UNITED STATES PATENT OFFICE.

JOSEPH JOHN RATHGEB, JR., OF NEW YORK, N. Y.

VENDING MACHINE.

1,272,096.

Specification of Letters Patent.

Patented July 9, 1918.

Application filed May 22, 1917. Serial No. 170,296.

To all whom it may concern:

Be it known that I, JOSEPH JOHN RATHGEB, Jr., a citizen of the United States, residing at New York, in the county of New York and State of New York, have invented new and useful Improvements in Vending Machines, of which the following is a specification.

The invention relates to vending machines and has for one of its objects the provision of such a machine having a coin operated gear train which drives step by step a vending wheel to each spoke of which is pivoted a carrier or receptacle, said receptacles emptying successively into a delivery chute.

Another object of the invention is to provide a vending machine which will automatically, after the last receptacle has been emptied, close the coin-slot to prevent further use until the machine is refilled.

Another object of the invention is to provide a fool proof machine which is of simple and practical construction and without complicated parts.

With these and other objects in view as will become more apparent as the description proceeds, the invention consists in certain novel features of construction, combination and arrangement of parts as will be hereinafter fully described, illustrated and claimed.

In the drawings,

Figure 1 is a top plan view with the casing partly broken away to disclose the internal mechanism.

Fig. 2 is a front elevation of the machine with the near casing wall removed.

Fig. 3 is a left side elevation of the machine.

Fig. 4 is a vertical sectional view partly in elevation on the plane of line 4—4 of Fig. 1.

Fig. 5 is a detail plan view showing the slot closure plate in operative position, and the parts immediately associated therewith.

Fig. 6 is a vertical sectional view through the coin carrier and entrance slot.

Fig. 7 is a detail sectional view through the delivery chute showing the break in the track and the position of the carriers adjacent thereto, and

Fig. 8 is a detail view of a part to be hereinafter more fully described.

Referring in detail to the drawings by numerals, 1 designates as an entirety the casing of the vending machine, which casing

may be of any considerable size in construction, having a top 2, front wall 3, rear wall 4, and side walls 5, 6. Journaled vertically within this casing is a main shaft or axle 7 to which is fixed a vending wheel generally 60 designated 8 and comprising a hub 9, spokes 10 and rim 11. The hub is fixed to the shaft 7 and the spokes are threaded into the periphery of the hub as shown. Each spoke extends across a horizontal track 12 concentric with the shaft 7 and having a break 13 over a discharge or delivery chute 14. The terminal 15 of the track stops at one side of the chute and the terminal 16 stops at the other side of the chute. The portion of the 70 track adjacent the end 16 is inclined downwardly toward the chute and the terminal 16 is beveled as shown. The track is suitably supported on columns 17 and secured in position thereon by screws 18 which extend 75 through the tubular columns and through the track.

To each of the spokes 10 is pivoted a carrier or receptacle 19 which is held in a substantially horizontal position by the track 80 to contain merchandise to be vended. The receptacles may be made of any suitable construction but are preferably formed as shown from a flat plate having one longitudinal edge portion turned to provide a sleeve 85 for the spoke and the other edge portion bent to form a retaining flange. As the receptacles are successively alined with the break 13, they swing by gravity downwardly into a vertical position to discharge 90 their load and on further rotation of the vending wheel are brought into engagement with the inclined terminal face 16 and gradually returned to their normal position.

The wheel is preferably driven by a train 95 of three spur gears. The inner most gear 20 is fixed to the shaft 7 adjacent the lower end thereof and meshes with an intermediate gear 21 held in position by a shaft 22. The gear 21 meshes with an outer gear 23 100 on a shaft 24. The shafts are secured to a gear plate 25 and are encircled by ball bearings 26 which support the gears.

The front wall 3 of the casing is formed with a vertical entrance slot 27 and a coin 105 carrying bar or block 28 is provided for co-operation with the slot 27 to receive the coin when it moves into the casing. The carrier is formed with a slot 29 in its upper face which is adapted for alinement with 110

the slot 27. The slot 29 has an inclined portion 30 which opens into the vertical portion 31 which extends entirely through the block and opens upon the inner side thereof.

5 A rack bar 32 is fixed to one end of the carrier, extends longitudinally therefrom, and is engaged by a gear 33 mounted on a shaft 34 having a turning handle 35 rotated externally of the casing. By turning the 10 handle to the left, the coin carrier will be operated to cause a coin 36 to rotate the gear 23. A sufficient rotation of the handle causes the coin to be moved from engagement with the gear wheel and to deposit in 15 the coin receptacle 37. The coin carrier slides on a shaft or rod 38 which is encircled by an expansive helical spring 39 to return the carrier to its normal position when released. If a coin of less than the 20 proper diameter is inserted into the entrance slot, it will not operate the machine, but will be returned to the user through the slot 40 in the plate 25. A coin of the proper size will, when inserted in the entrance slot, 25 roll down the incline 30 into engagement with the periphery of the gear wheel when the carrier is advanced.

To obstruct the coin passage when all of 30 the receptacles have been emptied, I provide a closure plate 41 which is pivoted at one corner as at 42 to a suitable support 43. This plate is swung in a horizontal plane over the coin slot in the carrier 28 by an arm 44 secured to the rim 11 of the vending 35 wheel. A spring pressed dog 45 engages the

wheel 23 and holds it against reverse rotation.

From the foregoing description taken in connection with the accompanying drawings, it will be evident that I have provided a very simple and practical vending machine having a vending wheel to the spokes of which are pivotally attached, carriers or receptacles which are moved by the wheel around a circular track, the track having a break which causes the receptacles to swing downwardly and empty. It will also be noted that the gear train is coin actuated and that it is only responsive to a coin of the proper diameter. 40 45

While I have shown and described the preferred embodiments of my invention, it will be clearly understood that I do not wish to be limited to this construction, but may make such changes as will fall within 50 55 the scope and spirit of the invention as claimed.

What I claim is:—

In a vending machine, a block mounted for movement and having a slot adapted to 60 partially receive a check, means for moving the block, a closure movably mounted adjacent the block, and means including an arm adapted to be operated step by step by the check when the block is moved to advance 65 the arm toward the closure and finally bring the arm in engagement with the closure and move the same over the slot in the block.

In testimony whereof I affix my signature.
JOSEPH JOHN RATHGEB, JR.
